UNITED STATES PATENT OFFICE.

WILLIAM SWINDELL, OF ALLEGHENY, PENNSYLVANIA.

GAS-PRODUCER.

SPECIFICATION forming part of Letters Patent No. 650,497, dated May 29, 1900.

Application filed March 9, 1900. Serial No. 7,993. (No model.)

To all whom it may concern:

Be it known that I, WILLIAM SWINDELL, of Allegheny, in the county of Allegheny and State of Pennsylvania, have invented a certain new and useful Improvement in Gas-Producers, of which improvement the following is a specification.

My invention relates to furnaces or producers employed for the generation of combustible gas by the combustion of low-grade or waste fuels; and its object is to provide means which shall be readily adaptable to gas-producers of the ordinary types, whereby air which is to be supplied either to the gas-producer or to a separate furnace or burner may be preheated by the combustion of the fuel in the producer.

To this end my invention, generally stated, consists in the combination of a gas-generating chamber and a plurality of surrounding air-heating pipes or conduits; also, in the combination of a gas-generating chamber, independent air-receiving chambers surrounding the lower end thereof, an upper air-discharge chamber, and a plurality of air-heating pipes or conduits built into the wall of the generating-chamber and connecting the receiving and discharge chambers.

The improvement claimed is hereinafter fully set forth.

In the accompanying drawings, Figure 1 is a view in elevation of a gas-producer, illustrating an embodiment of my invention; Fig. 2, a horizontal section through the same on the line *b b* of Fig. 1; Fig. 3, a partial vertical section on the line *a a* of Figs. 2 and 5; Fig. 3^a, a similar section on an enlarged scale; Fig. 4, a vertical section on the line *c c* of Fig. 5; Fig. 5, a horizontal section on the line *d d* of Fig. 4; and Figs. 6 and 7, partial sections on the line *e e* of Fig. 4 and on an enlarged scale, showing, respectively, different settings of the air-heating pipes.

My invention is herein shown as applied in connection with a gas-producer having a generating-chamber or fuel-chamber 1, to which fuel is supplied through upper feed-openings 2 and feed-hoppers 3. The main body of the generating-chamber 1 is of cylindrical horizontal section, and its lower portion is inwardly tapered or inclined toward the upper sides of two inclined grates 4, which are lo-

cated in the upper portion of the ash-pit 5. A gas-discharge flue 6, controlled by a valve or damper 6^a, leads from the upper portion 55 of the generating-chamber to a desired point of discharge, in this instance delivering gas through two end ports 6^b into the end of a drying-chamber 7, at which point the gas is mixed with heated air and burned. The general structural features above described are those which in different forms were known in the art prior to my invention and are not therefore in and of themselves claimed as of my present invention. 65

In the practice of my invention the producer, which is preferably of the general class or type of that above described, but which may be of any other known and preferred construction, is provided with a gas-generating 70 chamber 1, which is substantially surrounded near its lower end by air-receiving chambers 8, which are formed in the annular wall of the generating-chamber, preferably independently one of another, as shown in Fig. 2, 75 each chamber being provided with an air-admission port or opening 9, controlled by a door 10. The doors of adjoining receiving-chambers may be connected with operating mechanism whereby the air-admission port of one 80 chamber may be closed coincidently with and proportionately to the opening of that of an adjoining chamber. To this end the adjacent doors 10 (shown in Fig. 1) are connected to opposite ends of a chain 11, passing over 85 sheaves 12, journaled on the outside of the producer, the chain 11 being connected to an operating-rod 13, by movement of which in either direction closing movement may be imparted to one of the connected doors and 90 opening movement to the other.

The upper end of the gas-generating chamber is closed by an arched top or roof 14, through which pass the feed-openings 2 and suitable poke-holes 15. An annular air-discharge chamber 16, divided into two sections or compartments by a partition 17, is formed in the roof 14, adjacent to its periphery, and extends around the same to the sides of the central gas-discharge flue 6, each compartment of the chamber 16 communicating with an air-delivery flue 18, which extends along one side of the gas-discharge flue 6 to a discharge-port 19, the outer end of which adjoins 95 100

the delivery-port 6^b of the flue 6. In order to increase the heating-surface in the chamber 16, projections 20 may be formed on its inner wall, as shown in Fig. 5.

5 The air receiving and discharge chambers 8 and 16 are connected by a plurality of air heating pipes or conduits 21, which may be either of metal or clay and which are built into the wall of the gas-generating chamber 10 as nearly as may be entirely around the same, said pipes providing avenues for the traverse of air from the receiving to the discharge chamber, and in which the air which is supplied for admixture with the gas is preliminarily heated to a comparatively-high degree. The air-heating pipes may be set in any suitable and preferred manner—as, for example, being separated by bricks, as indicated in Fig. 6, or by bodies of sand, as in Fig. 7. As 15 shown in the drawings, the air-heating pipes of two of the air-receiving chambers 8 lead into one compartment of the air-discharge chamber 16, and those of the other two air-receiving chambers lead into the opposite compartment. Air may thus be shut off, as desired, by the doors 10 from portions of the set of pipes, which may be allowed to become highly heated while air is passing through other portions of the set, after which air may 25 be admitted to the more highly-heated pipes and shut off from those of lower temperature, as in the operation of a regenerative furnace. The provision of a plurality of air-heating pipes or conduits, substantially as above described, attains substantial advantages, both structural and resultant, which are not within the capacity of producer constructions in which flues or chambers in the walls are employed, as instanced in the art prior to my 30 present invention. The flues heretofore proposed are expensive to construct and found to rapidly deteriorate by breaking away in service, while the separate heating-pipes may be inexpensively set and are satisfactorily durable. They further provide the greatest practicable area of heating-surface and enable the air-supply to be thoroughly heated prior to 35 its admixture with the gas for combustion.

I claim as my invention and desire to secure 40 by Letters Patent—

1. The combination, in a gas-producer, of a

gas-generating chamber, and an annular series of vertical air-heating pipes built into the wall of and surrounding the generating-chamber.

55

2. The combination, in a gas-producer, of a gas-generating chamber, a lower air-receiving chamber and an upper air-discharge chamber each formed in the wall of the producer, and a plurality of air-heating pipes built into 60 the wall of the gas-generating chamber and connecting the air-receiving and air-discharge chambers.

3. The combination, in a gas-producer, of a gas-generating chamber, separate independent air-receiving chambers formed in the lower portion of the producer-wall, an upper air-discharge chamber in the producer-wall, and a plurality of air-heating pipes built into 65 the wall of the gas-generating chamber and connecting the air receiving and discharge chambers. 70

4. The combination, in a gas-producer, of a gas-generating chamber, separate independent air-receiving chambers formed in the 75 lower portion of the producer-wall, an air-discharge chamber located in the upper portion of the producer-wall and divided into independent compartments, a plurality of air-heating pipes built into the wall of the gas-generating chamber and connecting the air receiving and discharge chambers, and means for regulating air-supply from the air-receiving chambers to either compartment of the air-discharge chamber. 80

5. The combination, in a gas-producer, of a gas-generating chamber, a gas-discharge flue leading therefrom, an air-receiving chamber formed in the lower portion of the wall of the producer, a valve-controlled air-supply port 85 or opening in said chamber, an air-discharge chamber formed in the upper portion of the wall of the producer, air-discharge flues leading therefrom on opposite sides of the gas-discharge flue, and a plurality of air-heating 90 pipes built into the wall of the gas-generating chamber and connecting the air receiving and discharge chambers. 95
